UNITED STATES PATENT OFFICE.

JOHN EVANS, OF NEW BRUNSWICK, NEW JERSEY.

IMPROVEMENT IN OVERSHOES.

Specification forming part of Letters Patent No. 123,162, dated January 30, 1872.

Specification describing new and Improved Overshoes, invented by JOHN EVANS, of New Brunswick, in the county of Middlesex and State of New Jersey.

My invention consists of a cloth top and India-rubber bottom overshoe having a yoke of elastic India-rubber lined cloth inserted in place of a portion of the instep at the upper part removed, for stretching to allow the shoe to be put on, and contracting again to keep it snug and tight, the object being to dispense with the elastic gores heretofore used, which are objectionable, as it is only a small portion of the upper part of the shoe top that is required to stretch to put on the shoe, while the gores extend to the bottom and take much more of the elastic cloth than is needed, and they are not so easy on the foot, for the latter is subject to the contracting power of two pieces of the elastic cloth; whereas I use but one and have the same length of cloth to stretch as when the gores are used, for I may extend my yokes as far along the top as I please.

The drawing is a perspective view of a shoe with a yoke of elastic cloth applied to the instep according to my improvement.

A is the cloth part of the upper, and B the elastic cloth fitted in the upper edge of A at

the instep. Said yoke of elastic cloth is made wide—say an inch or thereabout, at the center of the instep, as necessary to allow of putting it on sufficiently easy, but varying according to the height of the shoe, and extends along the top at each side toward the heel one-third of the way, more or less, gradually tapering up to the top of the shoe, and is secured in any way preferred.

This yoke is preferable to the gores in that it is exactly in that part of the shoe that is required to stretch when putting it on or taking it off or by the action of the feet in walking. The shoe is therefore more symmetrical and natural than when the gores are used, and the stretching is at the sides.

Having thus described my invention, I claim as new and desire to secure by Letters Patent—

The improved manufacture, consisting of cloth-top overshoes with an elastic yoke B in the instep, substantially as specified.

The above specification of my invention signed by me this 21st day of November, 1871.

JOHN EVANS.
